UNITED STATES PATENT OFFICE.

JAMES HARRY KEIGHLY McCOLLUM, OF TORONTO, ONTARIO, CANADA, ASSIGNOR TO
GEORGE H. GOODERHAM AND JOHN WYCLIFFE LOWES FORSTER, BOTH OF TORONTO,
ONTARIO, CANADA.

AUTOMATIC TRAIN-STOP AND RECORDER.

1,185,920.

Specification of Letters Patent.

Patented June 6, 1916.

Application filed June 5, 1911. Serial No. 631,454.

To all whom it may concern:

Be it known that I, JAMES HARRY KEIGHLY McCOLLUM, a subject of the King of Great Britain, and resident of the city of 5 Toronto, county of York, Province of Ontario, in the Dominion of Canada, have invented certain new and useful Improvements in Automatic Train-Stops and Recorders, of which the following is a specification.

The invention relates to improvements in automatic train stops and recorders, as described in the following specification and illustrated in the accompanying drawings 15 that form part of the same.

The invention consists essentially in the novel construction and arrangement of parts, whereby an automatic application of the brakes is effected in the event of the train 20 passing a danger signal, and whereby an accurate record is made of the condition of the signals at the time of passing same.

The objects of the invention are, to minimize accidents on rail-ways, to automatically 25 stop the train in the event of the engineer failing to observe and act upon a danger signal set against him, and to devise a simple mechanism adapted to work in conjunction with present known signaling systems and 30 which will act to stop the train in the event of failure of any of the parts, and further to devise a means of keeping the engineer always alert by retaining a record of his run and the condition of all signals passed.

In the drawings, Figure 1 is a diagrammatic view of the invention showing the apparatus carried on the train partly in section and illustrating the manner of contact with the rail and operating member and the 35 electrical circuits connected therewith. Fig. 1^a is a diagrammatical plan view illustrating the wiring arrangement for the track circuit. Fig. 2 is a perspective view of the main air valve and operating shoe shown 40 partly broken away. Fig. 3 is a horizontal sectional view through the main air valve and shoe. Fig. 4 is an elevational diagrammatic view of a portion of a track-way showing the means for actuating the mechanism carried on the locomotive. Fig. 5 is a hori-

zontal sectional view through the line *a—b* Fig. 1.

Like numerals of reference indicate corresponding parts in each figure.

Referring to the drawings, 1 is a pipe 55 leading from the train line pipe of the air brake system of the train.

2 is a valve casing secured to the pipe 1 and having a tapered valve seat 3 formed therein. 60

4 is a valve arranged to close against the seat 3 and having its stem 5 slidably arranged in the spider 6 above the valve seat 3 and in the cross bar 7 below said valve seat, said stem having a shouldered portion 65 8 adapted to engage the cross bar 7 to limit the downward movement of the valve.

9 are a pair of electro-magnets secured to the cross bar 7 and extending downwardly therefrom and arranged one to each side of 70 the valve stem 5.

10 is an armature rigidly secured to the end of the stem 5 and arranged adjacent to the bottom ends of the cores of the magnets 9. The armature 10 is set so that on 75 the electro-magnets being energized, the pull of the magnets on the said armature will lift the valve 4 to its seat and will hold said valve closed against the train line pressure.

11 is a casing secured to or forming part 80 with the valve casing 2 and having a narrow passage 12 arranged at one side thereof leading to a circular chamber 13.

14 is a pipe leading from the lower end of the casing 11. 85

15 is a rotor journaled within the circular chamber 13 and having radially arranged buckets 16 arranged to extend into the path of the air passage between the passage 12 and the pipe 14 and adapted to be rotated by 90 the flow of air therethrough.

17 is a valve casing supported on a frame 18 which is rigidly connected to the locomotive and electrically insulated therefrom in any suitable manner, the actual connection 95 to the locomotive not being shown.

19 is a pipe connected to the pipe 14 and electrically insulated therefrom and leading to the valve casing 17. The valve casing 17 is cylindrical in form and has an air opening 100

20 in one of its ends and an arc shaped slot 21 extending therethrough at the upper side.

22 is a spindle rotatably secured in the ends of the casing 17 and projecting there-through, said spindle having a feather 23 ex-tending from one side thereof within the casing and a central hole 24 extending lon-gitudinally thereof. The outwardly ex-tending ends of the spindle 22 are slotted 10 longitudinally to a point close to the ends of the casing and provided with cross key slots 25.

26 is a shoe preferably formed of cast iron and having a pair of arms 27 formed 15 with heads 28 at their extremities adapted to fit into the longitudinal slots 29 in said spindle.

30 are key slots extending transversely through the heads 28 and adapted to register 20 with the slots 25 in said spindle.

31 are holes formed in the shoe 26 and ex-tending outwardly from the heads 28 to the extremity of said shoe, the inner ends open-ing laterally inward and registering with 25 the central hole 24 in the spindle 22.

32 are tapered split keys inserted through the key slots in the spindle 22 and extending through the slots in the heads 28, said tapered keys holding the inner faces of the 30 arms 27 in close engagement with the bot-tom of the slots 29 in said spindle and form-ing air tight joints therewith.

33 is a disk valve rotatably arranged within the casing 17 and fitting against one 35 end thereof, said valve having an arc shaped slot 34 and extending therethrough and ar-ranged so that when the shoe is in a hori-zontal position the end of said slot will be close to the air hole 20 in the end of the 40 casing.

35 is a flange projecting from the inner face of the valve 33 and partially encircling the spindle 22, said sleeve having a sector shaped notch 36 cut therein into which the 45 feather 23 of said spindle extends.

37 is an air hole through the spindle com-municating with the interior of the casing beyond the end of the sleeve 35.

38 is a pin secured to the valve 33 and ex-tending outwardly through the arc shaped 50 slot 21.

39 is a rod secured in the frame 18 extend-ing through a slot 40 in the shoe 26.

41 are spiral springs encircling the rod 39 55 and engaging the top and bottom sides of said shoe and holding it in a horizontal po-sition.

42 is a cylinder arranged adjacent to the valve casing 17 and held in fixed relation to the said valve casing.

43 is a piston operating in the cylinder 42.

44 is a link pivotally connected at one end to the outer end of said piston and at the other end to projecting end of the pin 38 se-cured to the valve 33.

45 is a handle rigidly secured to the pis-ton 43 and extending through the slot 46 in the cylinder 42.

47 is an electromagnet suitably supported outside of the cylinder 42 and having the 70 armature 48 extending through a hole in the wall of the cylinder and adapted to engage shoulder 49 formed on the outer end of said piston to hold it in its innermost position.

50 is a valve casing arranged adjacent to 75 the casing 2 and connected thereto by the pipe coupling 51.

52 is a pipe leading from the casing 50 to the cylinder 42 and formed with a suitable electrical insulating joint 53.

54 is a pipe entering the valve casing 50 between the pipe 51 and the pipe 52 and communicating with the main reservoir of the air brake system.

55 is a piston valve slidably arranged 85 within the casing 50 and having the portion 56 normally closing the opening to the pipe 51 and the portion 57 arranged partly clos-ing the pipe 52.

58 is an air hole in the bottom of the cas-ing 50 arranged below the portion 56 of the valve.

59 is an electro-magnet arranged at the top end of the casing 50 and adapted on be-ing energized to lift the valve 55. The pis-ton portions of the valve 55 are so arranged in relation to the pipe openings of the valve casing that on the raising of the valve the pipe 51 will be open and communication es-tablished between the main reservoir and 100 the pipe 52 through the pipe 54.

60 is a spring normally holding the valve 55 in its lowermost position. The electro-magnets 47, 9 and 59 are wired together in series and the circuit is electrically connect-ed at one end to the frame 18 and conse-105 quently to the shoe 26. The wire leading from the magnet 59 is connected to the frame of the vehicle and through the wheels forms an electric connection with the track 110 rails 61.

62 is an obstructing member arranged to the side of the track-way and formed with an arched upper surface curving from end to end, said member being arranged in the 115 path of the shoe 26 as the train moves in its travel.

63 is a wire connecting the metallic sur-face of the obstructing member 62 with a battery 64 arranged in the road bed.

65 is a wire electrically connecting the track rails 61 with the switch 65^a of a relay instrument 66 and the circuit to the battery is completed through the wire 67. When the switch 65^a is closed and the shoe 26 is in engagement with the obstructing member 62, the current from the battery 64 flows through said obstructing member and shoe and the frame 18 to and through the electro-magnets arranged in series.

68 is an ammeter gage electrically connected to the wire leading to the electro-magnet 47 and having its other terminal connected through a wire 69 to a contact instrument 70 to be used by the engineer as hereinafter explained.

71 is a train of gears operatively connected with the rotor 15 to the outside of the rotor casing.

10 72 is an arm pivotally supported from the frame 73 and spring held in a vertical position by the rod 74 having the springs 75 encircling the same between the lugs 76 extending from said frame.

15 77 are stops on the ends of the rod 74 adapted to limit the movement of the said rod and the arm 72.

78 is a connecting rod pivotally secured to the crank pin 79 on the outer one of the 20 train of gears 71 and at its other end pivotally connected to the arm 72 intermediate of its length.

80 is a spindle journaled at one end in a suitable bearing 81 and extending through 25 a threaded bearing 82 at the other end and threaded thereinto and having a reduced squared outer end 83.

84 is a drum rigidly secured to the spindle 80 intermediate of its length.

30 85 is a clock mechanism suitably supported from the frame 73 having a bearing 86 encircling the squared end of the spindle 80.

87 is a spur gear journaled in the bearing 86 and having a central squared orifice 35 through which the squared end 83 of the spindle 80 extends. The spindle 80 is thus operatively connected with the clock mechanism and is rotated thereby. The drum 84 is arranged to receive a suitable index

40 sheet having a suitable scale arrangement of hours printed thereon and a suitable pencil or point 88 is secured in the end of the arm 72 and arranged to engage the surface of the said index card and to trace a line

45 thereon as the drum rotates. The drum spindle being threaded into the bearing 82 moves longitudinally coincidently with its rotation and the point 88 thus traces a spiral mark upon the indicator sheet.

50 The relay 66 is arranged in the track circuit 89 and operates to close the switch 65^a for operating the semaphore and electrifying the obstructing member 62. The signaling system shown is of the class wherein 55 the semaphores are power held to "Clear," but it must be understood that the switch 65^a may be operated in any desirable manner.

In the operation of this device, as a train 60 in its travel passes each semaphore the shoe 26 comes in contact with the inclined surface of the stationary obstructing member 62 and said shoe is swung upwardly thereby. If the semaphore is at "Clear" the 65 metallic surface of the stationary obstruct-

ing member will form an electric contact with the shoe and the current flowing through the electro-magnets 9 and 59 causes the valves 4 and 55 to be operated. The closing of the valve 4 shuts off the train line 70 pipe and prevents the escape of air therefrom. As the shoe travels over the arched top of the obstructing member 62 it swings upwardly turning the spindle 22 and through the feather 23 coming in contact 75 with the side of the notch 36 in the sleeve of the valve 33 turns it on its seat moving the slot 34 into register with the air hole 20 in the valve casing, allowing the air within the valve casing and its adjoining parts to 80 escape. The rotary movement of the valve, through the pin 38 and connecting link 44 pushes the piston 43 inwardly into the cylinder 42. The electric current flowing through the electromagnet 47 holds the armature latch in its raised position so that it will not drop down and lock the piston. The simultaneous upward movement of the piston valve 55 opens communication between the pipe 51 and the air hole 58 and 90 simultaneously opens communication between the pipe 52 and the pipe 54 leading from the main reservoir. The flow of air through the pipe 52 exerts pressure against the piston 43 pushing it outwardly and 95 through the link 44 returning the valve 33 to its normal position.

The shoe 26 is normally held in a horizontal position by the springs 41 arranged to each side thereof and encircling the rod 39. 100 It will thus be seen that the shoe and the several valves will be operated as the train passes each signal, consequently the various working parts will be kept in the very best operative condition.

Before a train starts on its run the clock mechanism 85 is wound up and the drum set at its innermost position with a new index card placed thereon. The operation of the clock mechanism rotates the spindle 110 80 very slowly thereby rotating the drum and as the said spindle is threaded, its rotating movement causes it to move longitudinally through the threaded bearing 82 causing a spiral mark to be made upon the 115 index card. As the locomotive passes each "Clear" signal and the air within the chambers is allowed to escape, the rotor 15 is moved slightly by the inflow of air refilling the chambers and rotating the train of 120 gears 71, swings the arm 72 on its pivot thereby making a slight digression from the spiral line being traced on the drum 84.

The index card may be suitably ruled longitudinally or scaled off to indicate time 125 and the record made by the travel of the indicating pencil will show exactly the time at which each semaphore is passed and in the event of a semaphore indicating that a "Danger" signal has been passed, an excep-

tionally long digression in the record line will show, the operation in this case being hereinafter more fully explained.

The signal system being of the normal power held "Clear" type insures the electrifying of the obstructing member in the path of the shoe when the signal is at "Clear" but in the event of the signal being at "Danger" by the cutting out of the relay 66 the switch 65^a will be opened by gravity with the consequence that there will be no flow of current through the electro-magnets on the contact of the shoe with the obstructing member. The valve 33 is rotated by the upward swinging of the shoe 26 and as the slot 34 comes into register with the air hole 20 in said casing the air from the train line is allowed to escape, thereby making an application of the brakes and automatically stopping the train.

The escape of air through the valve casing 17 causes a flow through the valve casing 2 and chamber 13. The air flowing through the narrow passage 12 impinges against the blades of the rotor 15 causing said rotor to rotate and to operate the train of gears 71 thereby through the connecting rod 78 swinging the arm 72 on its pivot to make an extra long digression from the spiral line 30 being marked on the indicating card. The stop lugs on the ends of the rod 74 stop the movement of the gears but sufficient space is allowed to each side of the rotor blades to allow a free enough flow of air therearound 35 to insure the proper reduction in the train line pressure to apply the brakes. On the cessation of the flow of air through the chamber 13 the springs 75 acting on the rod 74 return the arm 72 to its normal position.

40 As there is no flow of current through the electro-magnets the downwardly spring held armature of the magnet 47 will on the inward movement of the piston drop into the notch therein, thereby locking it and the 45 valve 33 in the open position so that even though the shoe 26 has passed over the obstructing member it cannot return to its normal position to close the exit opening from the train line pipe.

50 91 is a wire electrically connected to the obstructing member and carried along on suitable posts beside the track for a short distance, the distance being such that the train will come to a stop before going beyond the length of said wire. When a train has thus been stopped the engineer may take the instrument 70 and getting down from his cab hook the said instrument on to the wire 91. As soon as the semaphore, 55 which he has passed is operated to "Clear" the flow of current through the said contact instrument 70 will indicate on the gage 68 which may be placed in the cab. The latch locking the piston will then be immediately 60 withdrawn by the energizing of the electro-

magnet 47 and coincidently the valve 55 will operate to direct the air pressure from the main reservoir against the said piston, thereby returning it to its normal position. The engineer may then proceed with his 70 train in the usual manner but he will of course have to explain why he passed a "Danger" signal, as the indicator gives a positive record of such passing. The apparatus thus insures proper vigilance on the 75 part of the engine operator and dispenses with the necessity of "Surprise tests."

In the ordinary running of the train and the operation of the mechanism in passing "Clear" signals the valve 4 is automatically 80 closed as described so that the temporary opening of the valve 33 allows the air in the intervening passages beyond said valve 4 to escape. There is, however, not sufficient area in said parts to make any substantial reduction 85 in the train line pressure on the re-opening of the valve 4 on the passing of the train past the electrified stationary obstructing member and no application of the brakes will be made. The valve 55 is returned to 90 normal by gravity or may be assisted by a suitable spring as shown and on returning to its normal position the air within the pipe 52 is allowed to escape above the upper piston portion of said valve and through 95 the upper end of the casing.

Provision is made so that in the event of the shoe 26 being accidentally broken proper notice will be given, the holes 31 being connected with the interior of the casing 17 in 100 the manner described will allow the escape of air from the train line thereby causing an application of the brakes and stopping the train.

The device throughout is so constructed 105 that in the event of it being disabled in any way the result is the stopping of the train.

What I claim as my invention is:—

1. In an automatic train stop, the combination with the air brake mechanism, of a 110 valve connected with the train line of said air brake, a shoe operatively connected to open said valve on every operation thereof, a stationary obstructing member arranged on the track-way in the path of said shoe 115 and adapted to move said shoe to open said valve, means for electrifying said obstructing member, and electrically operated means for closing the train line electrically connected to said shoe.

2. In an automatic train stop, the combination with the air brake mechanism, of a valve connected with the train line of said air brake, a shoe operatively connected to open said valve on every operation thereof, 125 a stationary obstructing member arranged on the track-way in the path of said shoe and adapted to move said shoe to open said valve, a suitable electric current supply electrically connected to said obstructing mem- 130

- ber and to the track, a switch arranged in the wiring from said electric current supply, an electric signal circuit connected with the track-way, means included in said electric signal circuit for holding said switch normally closed, and electrically operated means for closing the train line of the air brake electrically connected to said shoe and through the engine wheels to said track.
3. In an automatic train stop, the combination with the air brake mechanism, of a valve connected with the train line of said air brake, a shoe operatively connected with said valve, a stationary obstructing member arranged on the track-way in the path of said shoe and adapted to move said shoe to open said valve, a valve arranged in the pipe connection between the train line and the aforesaid valve, electrically operated means for closing the latter valve electrically connected to said shoe and to the train wheels, a partial electric circuit connected to the track-way and to said obstructing member and completing the electric circuit through the electric valve closing means, and means for opening and closing said electric circuit.
4. In an automatic train stop, the combination with the air brake mechanism, of a valve casing interposed in a branch from the train line of said air brake, a valve arranged in said casing adapted to close said branch, a valve casing connected with the aforesaid casing and having a port leading to the atmosphere, a valve in the latter casing closing said port, a shoe operatively connected with the latter valve, a stationary obstructing member arranged on the track-way in the path of said shoe and adapted to move said shoe to operate the valve connected therewith to open said port, electrically operated means for closing the first-mentioned valve electrically connected to said shoe, a partial electric circuit connected to the track-way and to said obstructing member and completing the electric circuit through the electric valve closing means, and means for opening and closing said electric circuit.
5. In an automatic train stop, the combination with the air brake mechanism, of a valve casing interposed in a branch from the train line of said air brake, a valve arranged in said casing adapted to close said branch, an electromagnet arranged within said casing, an armature connected with said valve and adapted on the energizing of said electro-magnet to move said valve to its closed position, a valve casing connected with the aforesaid casing, and having a port leading to the atmosphere, a valve in the latter casing closing said port, a shoe operatively connected with the latter valve, a stationary obstructing member arranged on the track-way in the path of said shoe and adapted to move said shoe to operate the valve connected therewith to open said port, a partial electric circuit connected to the track-way and to said obstructing member, and suitable wiring connecting said electro-magnet with said shoe and with the engine wheels.
6. In an automatic train stop, the combination with the air brake mechanism, of a valve casing interposed in a branch from the main line of said brake, a valve arranged in said casing adapted to close said branch, electrically operated means for closing said valve, a valve casing connected with the aforesaid casing and having a port leading to the atmosphere, a rotary valve arranged within the latter casing closing said port and having an opening therethrough adapted to be brought into register with said port, a shoe operatively connected with said rotary valve and rotatably supported from said casing and projecting outwardly therefrom, a stationary obstructing member arranged on the track-way in the path of said shoe and adapted to swing said shoe on its pivot to operate said rotary valve to open the port in said casing, a partial electric circuit connected to the track-way and to said obstructing member, and suitable wiring connecting said electric valve operating means with said shoe and the engine wheels.
7. In an automatic train stop, the combination with the air brake mechanism, of a valve casing interposed in a branch from the train line of said air brake, a valve arranged in said casing adapted to close said branch, electrically operated means for closing said valve, a valve casing connected with the aforesaid casing and having a port leading to the atmosphere, a spindle journaled in the ends of said casing and extending therethrough and having a feather laterally projecting therefrom within the casing, a disk valve rotatably supported on said spindle within said casing and having a centrally arranged sleeve portion formed with a sector shaped notch into which said feather extends, said valve also having an opening therethrough adapted to register with the port in said casing, a shoe rigidly connected to the extending ends of said spindle and projecting outwardly from said casing, a stationary obstructing member arranged in the track-way in the path of said shoe and adapted to swing said shoe to rotate said disk valve, a partial electric circuit connected to the track-way and to said obstructing member, and suitable wiring connecting said electric valve operating means with said shoe and the engine wheels.
8. In an automatic train stop, the combination with the air brake mechanism, of a valve casing interposed in a branch from the train line of said air brake, a valve arranged in said casing adapted to close said

- branch, electrically operated means for closing said valve, a valve casing connected with the aforesaid casing and having a port leading to the atmosphere, a spindle journaled in the ends of said casing and extending therethrough and having a feather laterally projecting therefrom within the casing and having a centrally arranged hole extending longitudinally thereof and an opening leading from said hole into the interior of said casing and slots cut in the ends thereof, a shoe having a pair of arms adapted to extend to each side of said casing and to fit into the notches in said 10 spindle, said shoe having holes extending longitudinally through said arms and communicating with the hole through said spindle, means for rigidly securing said arms within said slots, an obstructing member arranged on the track-way in the path of said shoe and adapted to swing said shoe on its pivot to operate said rotary valve to open the port in said casing, a partial electric circuit connected to the track-way and to said obstructing member, and suitable wiring connecting said electric valve operating means with said shoe and the engine 20 wheels.
9. In an automatic train stop, the combination with the air brake mechanism, of a valve casing interposed in a branch from the main line of said air brake, a valve arranged in said casing adapted to close said branch, electrically operated means for closing said valve, a valve casing connected with the aforesaid casing and having a port leading to the atmosphere, a rotary valve arranged within the latter casing closing said port and having an opening therethrough adapted to be brought into register with said port, a shoe operatively connected with said rotary valve and rotatably supported from said casing and projecting outwardly therefrom, a stationary obstructing member arranged on the track-way in the path of said shoe and adapted to swing said shoe on its pivot to operate said rotary valve to open the port in said casing, means for locking said valve in its open position, means for releasing said locking means, means for returning said valve to its normal position, a partial electric circuit connected to the track-way and to said obstructing member, and suitable wiring electrically connecting said electric valve operating means with said shoe and the wheels of the engine.
10. In an automatic train stop, the combination with the air brake mechanism, of a valve casing interposed in a branch from the train line of said air brake, a valve arranged in said casing adapted to close said branch, electrically operated means for closing said valve, a valve casing connected with the aforesaid casing and having a port lead-
- ing to the atmosphere, a rotary valve arranged within the latter casing closing said port and having an opening therethrough adapted to be brought into registry with said port, a shoe operatively connected with said rotary valve and rotatably supported from said casing and projecting outwardly therefrom, a stationary obstructing member arranged on the trackway in the path of said shoe and adapted to swing said shoe on its pivot to operate said rotary valve to open the port in said casing, a cylinder arranged adjacent to the latter valve casing, a piston operating in said cylinder, a link pivotally connected to said piston and to a pin rigidly secured to said rotary valve and extending through a slot in the end of said casing closed by said valve, a latch member arranged to engage said piston to lock the rotary valve in its open position, an electro-magnet electrically connected with said shoe and adapted to lift said latch to free said piston, electric wiring connecting said electric valve operating means with said magnet and with the engine wheels, a partial electric circuit connected to the track-way and to said obstructing member, and means for returning said piston and said rotary valve to their normal positions.
11. In an automatic train stop, the combination with the air brake mechanism, of a valve casing interposed in a branch from the train line of said air brake, a valve arranged in said casing adapted to close said branch, electrically operated means for closing said valve, a valve casing connected with the aforesaid casing and having a port leading to the atmosphere, a rotary valve arranged within said casing and having an opening therethrough adapted to register with said port, a shoe operatively connected with said valve, a stationary obstructing member arranged in the track-way in the path of said shoe and adapted to operate said shoe to rotate said valve to open said port, a cylinder arranged adjacent to said valve casing, a piston operating in said cylinder operatively connected with said rotary valve, means for locking said piston to retain said valve in its open position, a pipe leading from said cylinder, a valve casing connected with said pipe, a pipe connected to the latter valve casing leading from the main reservoir of the air brake, a piston valve arranged in the latter valve casing normally closing communication between the latter pipe and the pipe leading to said cylinder, an electro-magnet adapted to operate said piston valve to open communication between said pipes to allow a flow of air to said cylinder from the main reservoir, electrically operated means for releasing said piston holding latch, suitable wiring connecting said latch releasing means and the electric valve operating means and the elec-

tro-magnet operating said piston valve with said shoe and with the wheels of the engine, and a partial electric circuit connected to the track-way and to said obstructing member.

- 5 12. In an automatic train stop and recorder, the combination with the air brake mechanism, of a valve arranged in a branch from the train line of said air brake, a shoe 10 operatively connected with said valve, a stationary obstructing member arranged on the track-way in the path of said shoe and adapted to operate the said valve to open the train line, a rotor member interposed in 15 the air passage, and means operatively connected to said rotor member adapted to record the application of the brakes through the operation of the shoe.

13. In an automatic train stop and recorder, the combination with the air brake mechanism, of a valve arranged in a branch 10

from the train line of said air brake, a shoe operatively connected with said valve, a stationary obstructing member arranged on the track-way in the path of said shoe and 25 adapted to operate the valve to open the train line, a casing connected with said valve inclosing a circular chamber having an inlet and exhaust tangentially arranged, a rotor member having a plurality of buckets on its periphery and journaled in said casing, and means operatively connected to said rotor member adapted to record the application of the brakes through the operation 30 of the shoe. 35

Signed at the city of Toronto, county of York, Ontario, Canada, this 8th day of May, 1911.

JAMES HARRY KEIGHLY MCCOLLUM.
